UNITED STATES PATENT OFFICE.

FRANK L. LANGHAMMER, OF BRIDGEPORT, CONNECTICUT.

ATTACHMENT DEVICE.

1,187,155.

Specification of Letters Patent. Patented June 13, 1916.

Application filed August 2, 1913. Serial No. 782,627.

To all whom it may concern:

Be it known that I, FRANK L. LANGHAMMER, a citizen of the United States of America, and a resident of Bridgeport, Fairfield county, Connecticut, have invented a new and useful Improvement in Attachment Devices, of which the following is a specification.

My invention relates to attachment devices of the kind usually made by stamping the same out of sheet metal and has as its object the production of a device which will remain securely in place when closed while at the same time it may be readily adjusted with reference to its supporting means, when open.

Further objects and advantages will appear hereinafter in the more detailed description.

20 I have illustrated my invention in connection with the attaching of the lower edge of a brassière to one of the studs of a corset, a use for which my device is peculiarly adaptable.

25 In the drawings, Figure 1 is a perspective view showing my device in place on a tape depending from the front of a brassière and connected with the stud of a corset. Fig. 2 is a perspective view of the device 30 alone. Fig. 3 is a front elevation of the device in closed position. Fig. 4 is a vertical sectional view of the device as shown in Fig. 3. Fig. 5 is a vertical sectional view of the device showing the same as applied in Fig. 35 1, parts being broken away. Figs. 2 to 5 inclusive are on a somewhat enlarged scale.

Similar letters of reference indicate similar parts throughout the several views.

In the drawings *a* indicates a brassière in 40 position over the upper portion of a corset *b*, *c* is a tape of any suitable material, elastic, or non-elastic, attached in any suitable manner to the bottom of the brassière preferably in line with and fastened to the central 45 seam *d* of the brassière.

e, *e* indicate the studs of the front clasp of the corset, *f* indicates the attachment device.

The attachment device *f* comprises a back 50 plate *g* provided with a key-hole slot *h* to receive a stud *e*, a horizontal slot *i* to receive the tape *c* and ears *j*, *j* to act as bearings for pintles *k*, *k* on lever *l*. Lever *l* comprises a finger piece *m*, a serrated edge *n* bent at an 55 angle to the finger piece, and an outwardly

and downwardly extending lug *o* adapted to enter the narrow portion or neck of the key-hole slot *h* and, when in position, to take in behind the head of stud *e* as shown in Fig. 5, as shown, and thereby prevent movement 60 of the stud *e*. In said Fig. 5, *p* indicates the eye of the corset clasp in position over stud *e*.

In practice the tape *c* may be threaded through slot *i*, preferably from front to rear, 65 the slot *h* placed in position over stud *e*, the attachment device as a whole slid up or down on the tape to secure the requisite degree of strain and the lever *l* closed so that the serrated edge *n* squeezes tape *c* between 70 said serrated edge and the back plate. The finger piece *m* prevents the device from slipping off the head of the stud to which it is attached and the lug *o* prevents the stud from slipping under the finger piece. The 75 grip of serrated edge *n* on the tape and the angle of the lines of strain prevent the finger piece from accidentally rising and releasing the connection between the attachment device and the stud.

While I have illustrated the device as applied in connection with securing the lower edge of a brassière to a corset stud, it is obvious that the same may find further application in connection with any similar or 85 analogous use and I do not restrict myself to the use shown nor to the details of construction illustrated and described further than the scope of the appended claim demands.

90 What I claim is:

An attachment device for an apparel provided with a stud comprising a substantially smooth plate provided with a key-hole slot, 95 a lever pivotally mounted on said plate and a lug projecting from the end thereof and extending at an angle thereto, said lug being adapted to project into the slot and to lie in the path of the stud when the latter is positioned at the narrow end of said key-hole slot to positively prevent disengagement of said stud relative to said plate.

100 In testimony whereof I have signed this specification in the presence of two subscribing witnesses.

FRANK L. LANGHAMMER.
